UNITED STATES PATENT OFFICE.

EDWIN NORTON, OF MAYWOOD, ILLINOIS, ASSIGNOR TO THE AUTOMATIC VACUUM CANNING COMPANY, OF CHICAGO, ILLINOIS.

VACUUM-SEALING CAN.

SPECIFICATION forming part of Letters Patent No. 680,999, dated August 20, 1901.

Application filed November 3, 1900. Serial No. 35,317. (No model.)

To all whom it may concern:

Be it known that I, EDWIN NORTON, a citizen of the United States, residing in Maywood, in the county of Cook and State of Illinois, have 5 invented a new and useful Improvement in Vacuum-Sealing Cans, of which the following is a specification.

My invention relates to improvements in vacuum-sealing sheet-metal cans. 10 It consists in a vacuum-sealing sheet-metal can comprising in combination a can-body having a seaming-flange at its upper end, affording also a smooth shoulder or bearing for a packing-ring, and a cover having a packing-ring and a guide-flange adapting the cover to be hermetically sealed by a vacuum or atmospheric-pressure seal, the cover having also a seaming rim or flange folded into a double seam with the seaming-flange of the 15 can-body, thus additionally locking the cover thereto with great strength and rigidity and securely compressing and confining the packing between the cover and can-body, whereby the filled can after having its cover thus 20 hermetically sealed and secured thereto by the combined vacuum seal and the double seam is adapted to have its contents cooked to any extent required without danger of the internal steam - pressure generated in the 25 sealed can by the cooking operation weakening, injuring, or causing leaks or defects in the joint uniting the cover to the can-body.

In the accompanying drawings, forming a 30 part of this specification, Figure 1 is a central vertical section of a vacuum - sealing sheet-metal can, showing the cover loosely in place thereon and ready to be hermetically sealed thereto in vacuum by placing the filled can in the receiver of a vacuum-pump, exhausting the air therefrom and from the can, 35 and then forcing the cover home upon the can - body and restoring it to atmospheric pressure. Fig. 2 is a similar view showing the cover hermetically sealed and secured to the can - body by the vacuum or atmospheric-pressure seal; and Fig. 3 is a similar view 40 showing the cover additionally sealed and secured to the can-body by a double seam by folding together the seaming flanges or rims 45 on the cover and can-body.

In the drawings, A represents the body of a sheet-metal can, the same having a seaming-flange a , which also forms a smooth shoulder or bearing a' for the packing C, which is

compressed between the cover B and can- 55 body. The sheet-metal cover has a flange, shoulder, or guide b , which fits inside the can- body and causes the cover to properly seat itself both when placed loosely thereon to permit the air and gases or vapors to be ex- 60 hausted through the open mouth of the can when in the receiver and also when the cover is forced home upon the can to hermetically seal it thereto by the vacuum or atmospheric-pressure seal. The packing C surrounds the 65 guide or shoulder b and is compressed between the cover and the shoulder or seaming- flange a on the can-body. The cover B has also a seaming rim or flange b' , which is folded with the seaming-flange a into a double seam 70 b^2 , which additionally compresses and holds compressed the packing C and locks and se- cures the cover to the can with great strength, 75 firmness, and rigidity and in a perfectly un- yielding manner. This double seam b^2 also securely confines the packing C, so that no internal pressure generated in the sealed can by the subsequent cooking operation can force any pin-holes or even the minutest leaks through the packed joint uniting the cover 80 and can-body.

The vacuum or atmospheric-pressure seal collapses or inwardly curves the cover B, as illustrated in Fig. 3, by reason of the vacuum within the can and the atmospheric pressure 85 on the outside thereof.

I claim—

The combined vacuum seal and double- seam sheet-metal preserving-can comprising 90 a can - body having a seaming - flange at its upper end forming also a smooth seat or bearing for a packing, and a cover having a pack- ing and a guide - flange and hermetically sealed and secured to said can - body by a 95 vacuum or atmospheric - pressure seal, said cover being inwardly curved or collapsed and having also a seaming rim or flange folded into a double seam with said seaming-flange on the can-body; whereby the packed joint uniting the cover and can-body is adapted to 100 resist internal pressure generated in the sealed can by subsequent cooking of its contents, substantially as specified.

EDWIN NORTON.
